(57) **CLAIM**

The ornamental design for a bottle with bottom cup, as shown and described.

DESCRIPTION

FIG. 1 is a top right perspective view of a bottle with bottom cup showing my new design;

FIG. 2 is a bottom left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines immediately adjacent to the shaded areas represent an unclaimed boundary line between claimed and unclaimed surfaces while all other broken lines represent unclaimed subject matter. None of the broken lines form any part of the claimed design.

1 Claim, 7 Drawing Sheets

Related U.S. Application Data

No. 29/566,719, filed on Jun. 2, 2016, now Pat. No. Des. 786,617, which is a continuation of application No. 29/525,573, filed on Apr. 30, 2015, now Pat. No. Des. 758,132.
